UNITED STATES PATENT OFFICE.

EGBERT H. CASTLE, OF QUINCY, ILLINOIS, ASSIGNOR TO COMSTOCK-CASTLE STOVE COMPANY, OF QUINCY, ILLINOIS, A CORPORATION OF ILLINOIS.

GAS-COCK-LOCKING DEVICE.

Application filed March 21, 1925. Serial No. 17,362.

To all whom it may concern:

Be it known that I, EGBERT H. CASTLE, a citizen of the United States, and resident of Quincy, in the county of Adams and State 5 of Illinois, have invented new and useful Improvements in Gas-Cock-Locking Devices, of which the following is a description, reference being had to the accompanying drawings, which are a part of this specification.

This invention relates to improvements in gas cock locking devices, more particularly adapted for use on gas ranges wherein the oven is equipped with two burners.

Gas ranges of the afore-mentioned character are provided with two oven burners, one below the other, and the lower burner heats the oven for baking and the like, while the upper burner is used for broiling. In 20 ranges of this kind, it has been found that explosions are apt to occur if one burner is turned on while the other is lighted.

It is, therefore, the primary object of the present invention to provide an automatic 25 locking device applied to the gas cocks of an oven which will prevent one of the gas cocks being turned on if the other cock is already on.

A further object of the invention is to 30 provide a vertically movable bar connected to the gas cock handles and manually movable from one position to another to permit the operation of one of the gas cocks and the consequent locking of the other of the gas cocks.

A further object of the invention is to 35 provide a gas cock locking device which is readily attachable to the ordinary range having a two burner oven and requiring no alterations or modifications of the same.

A further object of the invention is to 40 provide a device of the character described which is of very simple construction, is inexpensive to manufacture, is strong and durable, and is well adapted for the purpose described.

With the above and other objects in view, the invention consists of the improved gas 45 cock locking device and its parts and com-

bination as set forth in the claims, and all 50 equivalents thereof.

In the accompanying drawing in which the same reference characters indicate the same parts in all of the views:

Fig. 1 is a fragmentary perspective view 55 of a gas stove showing the improved locking device applied to the oven burner cocks, one of the cocks being turned to the "on" position;

Fig. 2 is a detail view of the gas pipe and 60 the oven burner cocks, showing the locking device in adjusted position with the lower burner cock in "on" position;

Fig. 3 is a detail sectional view taken on line 3—3 of Fig. 1 and on a larger scale; 65

Fig. 4 is a detail sectional view taken on line 4—4 of Fig. 2 and on a larger scale;

Fig. 5 is an enlarged detail view taken on line 5—5 of Fig. 1; and

Fig. 6 is an enlarged detail view taken 70 on line 6—6 of Fig. 2; the gas cock being in closed position, however.

Referring to the drawings it will be seen that the numeral 8 indicates a gas range 75 having an oven 9 which is provided with an upper and a lower burner, both of which are supplied with gas by a vertical pipe 10, from which extend valves 11 and 12 for controlling the flow of gas to the upper and lower burners respectively. The cocks or valves 11 and 12 are provided with valve stems having suitable handles 13 and 14 for the operation thereof, the valves being opened when the handles are in a horizontal position, and closed when the handles are 80 in a vertical position.

In gas ranges of the type illustrated 85 wherein the oven is provided with two burners it is desirable to provide a means for preventing one of the burner valves 90 from being opened if the other is on, as an accidental opening of the other valve might cause an explosion from the escape of gas. Hence, the present invention resides particularly in the provision of a locking 95 bar or member 15 and its application to the burner valves or operating handles thereof. Said member consists of an elongated bar

or plate twisted or bent substantially in the form of an **S** as shown and having enlarged or flanged end portions 16 and 17, the vertical planes of the end portions being spaced by approximately ninety degrees. The lower end portion of the bar 15 is provided with an oval shaped opening 18 while the upper end portion of the bar is provided with an **L** shaped opening 19, portions of 10 said last-mentioned opening being in different planes with respect to each other.

The locking member 15 is applied to the gas range as shown with the handles 13 and 14 extending through the openings 18 and 19, the bar being vertically movable with respect to the valve stems and handles.

If it is desired to operate the handle controlling the valve of the upper burner, the locking member is adjusted in the position 20 shown in Fig. 1 so that the lower **L** portion of the opening 19 engages the valve stem. In this position the upper valve handle is free to be moved, but as the lower opening 18 engages the handle 14, as shown in detail in 25 Fig. 5, movement of said handle is prevented and the consequent opening of the valve of the lower burner. However, if it is desired to operate the valve for the lower burner and the handle 14 therefor, the valve handle 13 30 must be closed and the locking bar 15 is then lowered and given a slight turn to the left. In this position the upper portion of the opening 19 engages the valve stem of the upper burner and the flanged portion of the bar 35 is positioned adjacent the handle 13 to prevent movement thereof. The lower end portion of the locking bar seats upon the stem portion of the lower handle, the position of the bar being shown in Figs. 2, 4, and 6, and 40 the lower handle 14 is free to be moved, but the upper handle 13 is prevented from movement. In this manner the locking bar forms an effective check against movement of one 45 of the valve handles when the other is turned to the "on" position.

From the foregoing description it will be seen that the improved gas cock or valve locking device is of very simple and novel construction, and is well adapted for the 50 purpose set forth.

What I claim as my invention is:

1. The combination with a gas range having two burners, of a valve, valve handle, and valve handle stem for each burner, and 55 a bar member loosely carried and supported only by one of said valve handles and one valve handle stem and movable longitudinally with respect thereto to either of two operative positions, one of said valve handles 60 being directly engaged and locked against substantial movement by said bar when it is in one operative position, and the other handle locked when the bar is in reverse position.

65 2. The combination with a gas range hav-

ing two burners, of a valve handle, and valve handle stem for each burner, and a curved bar member loosely carried only by one of said valve handles and one of said valve handle stems and manually movable 70 longitudinally with respect thereto to either of two operative and valve handle engaging positions, one of said valve handles being locked against movement by said bar when it is in one operative position, and the other 75 handle locked when the bar is in reverse position.

3. The combination with a gas range having two burners, of a valve for each burner, valve handles therefor, and a unitary valve 80 locking member engaging only said valve handles and being longitudinally and turnably movable to two positions of adjustment, one of the valve handles being prevented from movement by contact with the valve 85 locking member when the same is in one position of adjustment, and the other handle locked when the locking member is in reverse position.

4. The combination with a gas range having two burners, of a valve for each burner, valve handles therefor, and a valve locking member having an opening in one of its end portions through which one valve handle extends when locked, said valve locking member 90 having two positions of adjustment and one of the valve handles being prevented from movement by contact with the valve locking member when the same is in one position of adjustment, and the other handle 95 locked when the locking member is in reverse position.

5. A locking device for oven burner gas cocks, consisting of an **S**-shaped bar having enlarged end portions, the upper end portion 105 being provided with an **L**-shaped opening and the lower end portion being provided with an oval opening, both of said openings being arranged for the reception of gas cocks.

6. The combination with a gas range having a two burner oven, of a valve for each burner, valve handles therefor, and an **S**-shaped and twisted bar having enlarged end portions in different planes, the upper end portion being provided with an **L**-shaped opening and the lower end portion being provided with a curved opening, the valve handle of the upper burner valve being extended through said **L**-shaped opening and the valve 115 handle of the lower burner valve being extended through said lower opening, said bar having two positions of adjustment and one of the valve handles being prevented from movement by contact with one of the enlarged end portions of the bar when the same is in one position of adjustment, and the other handle locked when the bar is in reverse position.

7. The combination with a gas range hav-

ing two burners, of a valve for each burner, valve operating means therefor, and a longitudinally and turnably movable valve locking member, there being a slot and projection engagement between the locking member and the valve operating means, said valve locking member having two positions of adjustment and one set of the valve oper-

ating means being prevented from movement by contact with the valve locking member 10 when the same is in one position of adjustment, and the other set of valve operating means locked when the valve locking member is in reverse position.

In testimony whereof, I affix my signature.
EGBERT H. CASTLE.
